United States Patent Office

Des. 213,212

Patented Jan. 14, 1969

213,212

MOBILE

Richard L. Maxwell, Belleville, N.J., assignor to J. L. Prescott Co., Passaic, N.J., a corporation of New Jersey

Filed Feb. 16, 1968, Ser. No. 10,609

Term of patent 14 years

U.S. Cl. D34—15
Int. Cl. D21—02

FIG. 1

The drawing has been lined for color.

The essential features of my design reside in the full line disclosure.

I claim:

The ornamental design for a mobile, as shown and described.
